UNITED STATES PATENT OFFICE.

ERIC R. LUNDIUS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,295,909.

Specification of Letters Patent.

Patented Mar. 4, 1919.

Application filed May 11, 1918. Serial No. 233,915.

To all whom it may concern:

Be it known that I, ERIC R. LUNDIUS, a citizen of the United States, residing at Brooklyn, in the county of Kings, State of New York, have invented certain new and useful Improvements in Telephone-Exchange Systems, of which the following is a full, clear, concise, and exact description.

This invention relates to telephone exchange systems, and more particularly to such systems of the central energy type which employ trunk circuits for establishing connections from a switchboard operator's position to a desk-operator's position.

15 In systems of this type, the switchboard operator's link circuit is equipped with a key for ringing purposes, and when connection is made with a trunk circuit extending to a desk-operator's position, the switchboard or originating operator may ring thereon and continue to ring even after the desk operator has answered. In such systems heretofore employed, when ringing continues after the desk operator has answered, very disagreeable clicks are produced in the receiver of the answering operator.

It is the object of this invention to produce a system of this character in which the production of such disagreeable clicks in the receiver of the answering operator is avoided.

In accordance with this invention, a normally open trunk circuit extending from a switchboard operator's position to another switchboard or desk is provided with means which functions when the desk operator answers to connect across the trunk circuit a relay which is non-responsive to ringing current, but which responds to direct current connected with the trunk circuit upon the disconnection of ringing current therefrom to complete the connection to the desk.

For a more complete understanding of this invention, reference should be had to the following description considered in connection with the accompanying drawing illustrating one embodiment thereof.

As shown in the drawing, a trunk circuit A extends from a first to a second switchboard. At the first switchboard which may be designated as switchboard X, there is provided a cord circuit B, by means of which connection may be made from a calling telephone line (not shown) and the trunk circuit A. This cord circuit B may also be em-

ployed by the operator for originating a call over the trunk circuit A. At the second switchboard which may be designated as switchboard Y, there is provided a cord circuit C by means of which the operator there- 60 at may make connections with the trunk circuit in answering calls incoming thereover. The apparatus shown to the left of the dotted line 1—1 is located at the switchboard X and that shown to the right of this dotted line 65 may be located at the switchboard Y. The switchboard X may for convenience be considered as an originating operator's position, while the switchboard Y may be considered the desk of a chief operator, trouble 70 operator or supervisory operator.

The operator at the originating position X, desiring to establish a connection to the desk position Y, inserts plug 5 of the cord circuit B into jack 6 of the trunk circuit A, 75 whereupon calling supervisory lamp 7 is lighted and relay 8 operated over a circuit from battery through the lamp 7, resistance 9, sleeve contacts of the plug 5 and the jack 6, normal contact of relay 10, upper normal 80 contact of relay 12, winding of relay 8 and contact 11 of relay 12 to ground. Relay 8 in operating causes the lighting of lamp 13 over a circuit from battery through the lamp 13, contact 14 of relay 12 and the contact of 85 relay 8 to ground. Since the cord circuit B is provided with a ringing key 14, the operator at the originating position, while it is not at all necessary, may actuate this ringing key, and if it is actuated, it is very desirable 90 that connection through to the desk operator be delayed until after the ringing key has been restored to normal position. The manner in which this is brought about will more fully hereinafter appear. 95

The lighting of the lamp 13 serves as a signal to the desk operator, who, upon observing the lighted condition thereof, may answer by inserting plug 20 of the cord circuit C into jack 21. Thereupon lamp 22 lights and relay 10 operates over a circuit from battery through the lamp 22, resistance 23, sleeve contacts of the plug 20 and the jack 21, lower winding of relay 10 and contact 24 of relay 25 100 to ground. Relay 10 in operating opens the circuit of relay 8, thereby causing its deenergization and the effacement of the lamp 13. Relay 10 in operating also closes its contact 26, thereby including relay 12 in 110

circuit with the sleeve strand of the trunk circuit, whereupon relay 12 operates. Relay 12 in operating completes a locking circuit for itself through its contact 27, and due to the closure of its contacts 28 and 29, relay 8 is bridged across the talking strands of the trunk circuit, in series with a relay 30 which is of high impedance to high frequency talking currents but not necessarily 10 to low frequency ringing current. Relay 8 is responsive to direct current, but is non-responsive to ringing current. That is, while the armature of this relay 8 will be partially attracted when the winding thereof is traversed by ringing current, the contact will not be maintained closed under such circumstances. Therefore if the ringing key 14 is actuated at the time relay 8 is connected across the talking circuit, the contact of relay 8 will not be closed. This contact of relay 8 controls the circuit of relay 25 which in turn controls the completion of the talking circuit through to the desk operator. Upon the 20 restoration of the ringing key 14 to normal position, ringing current is disconnected from the trunk circuit and direct current substituted therefor, whereupon relays 8 and 30 operate over a circuit from battery 30 through the winding of supervisory relay 31, ring contacts of the plug 5 and the jack 6, contact 28 of relay 12, winding of relay 8, contact 29 of relay 12, winding of relay 30, contact 32 of relay 10 and tip contacts 35 of the jack 6 and the plug 5 to ground. Supervisory relay 31 also operates over this circuit to establish a shunt circuit including resistance 33 about the lamp 7, which is thereby effaced, indicating to the originating 40 operator that the desk operator has answered. Upon the operation of relays 8 and 30, relay 25 operates over a circuit from battery through its winding and the contacts of relays 30 and 8 to ground. Relay 45 25 in operating opens its normal and closes its alternate contacts. The closure of the alternate contacts connects the talking circuit through to the desk. The opening of contact 24 of relay 25 removes the short 50 circuit from the upper winding of relay 10 which is thereupon included in circuit with the lamp 22. Lamp 22 is thereby effaced. Since, while the relay 25 is deenergized the lamp 22 of the connected cord circuit is 55 lighted and when the relay is energized the lamp is effaced, this relay may be termed a signal control relay. Before inserting plug 20 of the cord circuit C into the jack 21 of the trunk circuit A, or immediately thereafter, the desk operator may actuate 60 listening key 34 to connect the telephone set in circuit. Either upon the restoration of ringing key 14 to normal position or upon the effacement of the lamp 7, the originating 65 operator may actuate listening key 42 to

connect this operator's telephone set in circuit. Both telephone sets being connected and the talking circuit being completed by the operation of relay 25, the operators may now converse. At the conclusion of the 70 conversation, the plugs may be withdrawn from the jacks, whereupon all apparatus is restored to normal condition.

It may happen that the desk operator connects the cord circuit C with the trunk 75 circuit A without actuating the listening key 34. When the originating operator's telephone set is connected in circuit, upon the actuation of the listening key 35, following the effacement of the supervisory 80 lamp 7, this operator will find that the desk operator has not connected her telephone set in circuit. It will be necessary therefore for the originating operator to rering (or resignal) the desk operator. This is 85 brought about by repeatedly withdrawing the plug 5 from and reinserting it into the jack 6, thereby to cause the flashing or intermittent operation of the lamp 22 associated with the cord circuit C. The withdrawal of the plug 5 from the jack 6 releases relays 12, 8, 30 and 25. The closure of contact 24 of relay 25 short-circuits the upper winding of relay 10, whereupon lamp 22 is lighted. The opening of the alternate 95 contacts of relay 25 opens the talking conductors of the trunk circuit, and the closure of the upper and lower normal contacts of this relay 25 connects resistances 35 and 36 in shunt of condensers 37 and 38, thereby 100 to discharge these condensers, so that upon the subsequent energization of relay 25, the connection of the condensers 37 and 38 in the talking conductors will take place when the condensers are in discharged condition. 105 In this manner there will be no discharge over the talking conductors upon their closure at the alternate contacts of relay 25. The reinsertion of the plug 5 into the jack 6 causes the energization of relay 12, followed in turn by the energization of relays 8, 30 and 25. Relay 25, upon being energized, opens its contact 24 to include the upper winding of relay 10 in circuit with the lamp 22, thereby to efface the lamp. 110 The closure of the alternate contacts of relay 25 completes the talking circuit to the desk. The lamp 22 will be lighted each time the plug 5 is withdrawn from the jack 6. The desk operator observing the intermittent lighting of the lamp 22, actuates listening key 34 to connect the telephone set in circuit.

If a calling subscriber's line is connected by way of the cord circuit B and the trunk 12 circuit A to the desk, the desk operator may then converse with the calling subscriber. If this is an information desk, the desk operator, after giving the calling subscriber such information as may be desired, may 13

wish to signal the originating operator. This may be done by repeatedly actuating a key 40 to cause the flashing or intermittent operation of the supervisory lamp 7. Upon the closure of the contact of key 40, relay 10 is short-circuited and deenergized, whereupon it releases its armatures. Relays 31, 8, 30 and 25 are thereby deenergized. Relay 31, upon being deenergized, opens the shunt circuit about the lamp 7 which thereupon lights. Relay 25, upon being deenergized, opens the contacts in the talking conductors and completes the shunt circuits about the condensers 37 and 38 to cause the discharge thereof. Upon the opening of contact of key 40, relay 10 immediately operates, connecting relays 8 and 30 in bridge of the talking conductors, whereupon these two relays and the supervisory relay 31 operate. The operation of supervisory relay 31 causes the effacement of the lamp 7, and the operation of relays 8 and 30 causes the operation of relay 25 to close the talking conductors. The lamp 7 is lighted upon each closure of the contact of the key 40. The intermittent lighting of this lamp 7 serves as a signal to the originating operator who may then actuate listening key 42 to connect the telephone set in circuit.

One of the other of the operators' telephone sets may be in circuit when the originating operator is reringing, or when the desk operator is signaling the originating operator, so that the provision of the shunt circuits about the condensers 37 and 38 serves a very useful purpose in reducing the clicks which may be produced in the operators' receivers while the reringing and signaling operations are taking place.

What is claimed is:

1. A telephone exchange system comprising a trunk circuit having normally open talking conductors extending from a first to a second switchboard, a link circuit at the first switchboard, a signaling device at the second switchboard, a relay in the trunk circuit responsive to the connection of the link circuit therewith for operating the signaling device, a link circuit at the second switchboard, means in the trunk circuit responsive to the connection of the second link circuit therewith for connecting the relay in bridge of the talking conductors, and means responsive after the establishment of the bridge to close the normally open talking conductors.

2. A telephone exchange system comprising a trunk circuit having normally open talking conductors extending from a first to a second switchboard, a link circuit at the first switchboard, a signaling device at the second switchboard, a relay in the trunk circuit responsive to the connection of the link circuit therewith for operating the signaling device, a link circuit at the second switchboard, a pair of relays in the trunk circuit

responsive to the connection of the second link circuit therewith and coöperating to connect the first relay in bridge of the talking conductors, means for energizing the first relay upon the establishment of the bridge, and a relay operated upon the energization of the bridged relay to close the normally open talking conductors.

3. A telephone exchange system comprising a trunk circuit having normally open talking conductors extending from a first to a second switchboard, means associated with the trunk circuit for signaling from the first to the second switchboard, a link circuit at the second switchboard, a relay, means in the trunk circuit responsive to the connection of the link circuit therewith for connecting the relay in bridge of the talking conductors, and means responsive after the establishment of the bridge to close the normally open talking conductors.

4. A telephone exchange system comprising a trunk circuit having normally open talking conductors extending from a first to a second switchboard, a link circuit at the first switchboard connected with the trunk circuit, a relay, a link circuit at the second switchboard, means in the trunk circuit responsive to the connection of the second link circuit therewith for connecting the relay in bridge of the talking conductors, means for energizing the bridged relay over the connected trunk and first link circuits, and means responsive to the energization of the bridged relay for closing the normally open talking conductors.

5. A telephone exchange system comprising a trunk circuit having normally open talking conductors extending from a first to a second switchboard, a link circuit at the first switchboard connected with the trunk circuit, a link circuit at the second switchboard, a relay, a second relay in the trunk circuit responsive to the connection of a link circuit therewith for connecting the first relay in bridge of the talking conductors, means associated with the first link circuit for energizing the bridged relay, and a relay responsive to the energization of the bridged relay for closing the normally open talking conductors.

6. A telephone exchange system comprising a trunk circuit having talking conductors extending from a first to a second switchboard, a link circuit at the first switchboard, a signal control relay in the trunk circuit operating over a circuit independent of the talking conductors upon the connection of the link circuit with the trunk circuit, a link circuit at the second switchboard, means in the trunk circuit responsive to the connection of the second link circuit therewith for connecting the signal control relay in bridge of the talking conductors, and a second signal control relay operating after the estab-

lishment of the bridge to close the normally open talking conductors.

7. A telephone exchange system comprising a trunk circuit having talking conductors extending from a first to a second switchboard, a link circuit at the first switchboard, a signal control relay in the trunk circuit operating over a circuit independent of the talking conductors upon the connection of

5 the link circuit with the trunk circuit, a link circuit at the second switchboard, a pair of relays in the trunk circuit responsive to the connection of the second link circuit therewith and coöperating to connect the signaling control relay in bridge of the talking conductors, means associated with the first link circuit for energizing the bridged relay, and a second signal control relay responsive to the energization of the bridged

10 relay.

8. A telephone exchange system comprising a trunk circuit having normally open talking conductors extending from a first to a second switchboard, a link circuit at the 25 first switchboard connected with the trunk circuit, means in the link circuit for connecting a source of ringing current with the talking conductors, a source of direct current at the first switchboard, a link circuit at the 30 second switchboard, a relay connected in bridge of the talking conductors upon the connection of the second link circuit with the trunk circuit and non-responsive while ringing current is connected therewith but responsive to the direct current connected with the talking conductors upon the disconnection of the ringing current therefrom, and means operating upon the response of the 35 relay to close the normally open talking conductors.

9. A telephone exchange system comprising a trunk circuit having normally open talking conductors extending from a first to a second switchboard, a link circuit at the 45 first switchboard connected with the trunk circuit, means in the link circuit for connecting a source of ringing current with the talking conductors, a source of direct current at the first switchboard, a link circuit at the 50 second switchboard, a relay connected in bridge of the talking conductors upon the

connection of the second link circuit with the trunk circuit and non-responsive while ringing current is connected therewith but responsive to the direct current connected with the talking conductors upon the disconnection of the ringing current therefrom, and a relay energized upon the response of the bridged relay to close the normally open talking strands.

10. A telephone exchange system comprising a trunk circuit extending from a first to a second switchboard and having normally open talking conductors and a signaling conductor, a signaling device at the 65 second switchboard, a link circuit at the first switchboard, a relay energized over the signaling conductor upon the connection of the link circuit with the trunk circuit to operate the signaling device, a link circuit at the 70 second switchboard, means in the trunk circuit responsive to the connection of the second link circuit therewith for connecting the relay with the talking conductors, and means responsive upon the connection of the 75 relay with the talking conductors for closing the normally open talking conductors.

11. A telephone exchange system comprising a trunk circuit extending from a first to a second switchboard and having normally open talking conductors and a signaling conductor, a signaling device at the 80 second switchboard, a link circuit at the first switchboard, a relay operating over the signaling conductor upon the connection of the link circuit with the trunk circuit to control the signaling device; a link circuit at the second switchboard, a relay in the trunk circuit responsive to the connection of a second link circuit therewith for disconnecting the 85 first relay from the signaling conductor, a third relay coöperating with the second relay to connect the first relay in bridge of the talking conductors, means in the first link circuit for energizing the bridged relay, and a fourth relay responsive to the energization of the bridged relay for closing the normally open talking conductors.

In witness whereof, I hereunto subscribe my name this 8th day of May A. D. 1918. 100

ERIC R. LUNDIUS.
